UNITED STATES PATENT OFFICE

163,912

COMBINED CONTAINER AND SLICER

Harold F. Taylor, Springfield, Ohio, assignor to
Tapco, Inc., Springfield, Ohio, a corporation of
Ohio

Application September 2, 1947, Serial No. 141,162

Term of patent 14 years

(Cl. D44—29)

To all whom it may concern:

Be it known that I, Harold F. Taylor, a citizen of the United States, residing at Springfield, Clark County, Ohio, have invented a new, original, and ornamental Design for a Combined Container and Slicer, of which the following is a specification, reference being had to the accompanying drawing, forming a part thereof, in which Fig. 1 is a perspective view of a combined container and slicer embodying my new design;

Fig. 2 is a rear view thereof, looking from the left of Fig. 1 with the cover removed; and

Fig. 3 is a perspective view of the assembled container and slicer showing the transparent nature thereof.

I claim:

The ornamental design for a combined container and slicer substantially as shown.

HAROLD F. TAYLOR.
